EDWIN H. SCHMIDT, OF INSPIRATION, ARIZONA.

BALL-MILL.

1,351,793.

Specification of Letters Patent.

Patented Sept. 7, 1920.

Application filed May 9, 1919. Serial No. 295,933.

To all whom it may concern:

Be it known that I, EDWIN H. SCHMIDT, a citizen of the United States, residing at Inspiration, in the county of Gila, State of Arizona, have invented certain new and useful Improvements in Ball-Mills; and I do hereby declare the following to be a full, clear, and exact description of the invention, such as will enable others skilled in the art 10 to which it appertains to make and use the same.

This invention relates to ball-mills and particularly to an arrangement by which wear on the liners of such mills may be detected before it has progressed to such a degree that there is danger of the mill becoming damaged.

Ball-mills of usual construction comprise a rotary shell provided upon its inner face 20 with liners formed of hardened steel, against which the balls and the material being ground impinge as the shell rotates. Under the continual wear to which these liners are subjected during the operation of the mill, 25 they will in time be reduced to such thinness that they will break through and expose the shell to the action of the balls. If this condition is not detected the shell will be quickly worn through, and the mill may 30 be seriously damaged. The liners are not conveniently accessible for inspection, and it is necessary to shut down the mill, and even remove some of its parts in order to permit examination of the liners. This 35 causes a loss of time in the operation of the mill, and a consequent decrease in its efficiency. So many factors enter into the question of the life of the liners that it is difficult to predict beforehand how long any 40 particular liner will last. The efficiency of the mill will be still further reduced if it has to be stopped for frequent inspection, as different liners will be subject to different amounts of wear according to their location 45 in the mill, and one must keep watch upon all of the liners in order to insure that worn ones may be replaced before damage occurs.

It is an object of this invention to overcome these disadvantages of ball-mills of the usual construction by providing an arrangement by which the worn condition of the liners may be detected without the necessity of stopping the mill and making an actual inspection of the liners. The arrangement is of simple construction and may be easily applied to existing mills with-

out any substantial changes in their structure.

In accordance with the invention there is provided in connection with each liner section, an arrangement whereby some of the contents of the mill will be permitted to escape if the corresponding liner section becomes worn to such an extent that it should be replaced, thus giving an indication of the 60 condition of the liners that may be observed even while the mill is in operation. The invention may be embodied in various forms, some of which are shown in the accompanying drawings, in which,

Fig. 1 is a sectional view through the central portion of the shell of a mill showing the liners in place with one form of the invention applied thereto;

Fig. 2 is an enlarged sectional view of one 75 of the indicating or sentinel bolts employed with the arrangement of Fig. 1;

Fig. 3 is a sectional view of a liner with a pipe instead of a bolt;

Fig. 4 is a similar view showing another 80 form of bolt that may be used; and

Fig. 5 is a similar view showing the indicating device formed as a part of the liner projecting through the shell.

The ball-mill, which may be of any preferred construction, and which is not shown in detail herein, comprises a shell 10 upon the interior of which are liners 11 formed of suitable hardened steel and retained in place by bolts 12 having their heads countersunk 90 in the thicker portions of the liners. The liners are shown of a shape particularly well adapted to coöperate with the balls of the mill in producing a grinding effect, but it will be understood that the liners may be of 95 any other shape, and that the invention is equally applicable to all liners.

In accordance with the embodiment of the invention shown in Fig. 1, there is associated with each liner section one or more indicating or sentinel bolts 13, preferably having their heads countersunk within the liner at the point where maximum wear occurs. These sentinel bolts will usually be applied to the liner sections at points midway between their ends, or, in other words, at the central zone of the mill. Each of the bolts is provided with a bore or socket 14 extending part way into the head 15, and the bolts are threaded to permit retaining nuts 16 to 105 be screwed thereon. The bolts are countersunk within the liners so that as the liners

wear away, the heads of the bolts will become exposed and ultimately worn away with the liners, thus placing the bores in communication with the interior of the mill, and allowing water and pulp to seep or leak through the bolts to give an indication of the worn condition of the liners, whereupon the mill may be stopped for repairs. The sentinel bolts may be formed of either hard or soft metal, and of different sizes and shapes according to the particular liners with which they are to be used.

Instead of bolts, short pieces of pipe 17 may be screwed into sockets 18 in the liners, as shown in Fig. 3. These pipes project through the shell of the mill and may be clamped in place by nuts 19. With this arrangement when the liner wears away so that the inner end of the pipe is opened, communication will be established with the interior of the mill, and the leakage of material therefrom will give an indication of the worn condition of the liner.

Instead of employing bolts having bores or sockets as described above, solid bolts 20, such as shown in Fig. 4, may be employed. In this case, the head of the bolt is countersunk in the liner, and the bolt is held in place by a nut 21. The head of the bolt will ultimately be worn away as the liner wears down, and when this occurs the shank of the bolt will drop out, this, in itself, giving an indication of the worn condition of the liner, but, in addition some of the material within the mill will be discharged through the aperture thus produced, and will give a further indication of the worn condition of the liner. It will be noted that the liners are held in place by two bolts, the heads of which may be so proportioned and which may be set different distances within the liners so that one head will wear off before the other one does, whereupon the one worn away will either drop out or allow material to escape through its bore, while the liner is still securely held in place by the other bolt. Obviously it would be a disadvantage to have the liner held in place by but a single bolt, subject to wear, which, when worn away, would release the liner entirely from the shell thus exposing that part of the shell to wear, and also releasing an unduly large piece of metal within the shell which would tend to damage it.

In addition to the modifications described above the invention may also be embodied in arrangements that do not require the use of separate members, such as bolts or pipes. One such arrangement is shown in Fig. 5 wherein the liner is provided with one or more knobs or projections 22 extending from its outer face opposite the zone of maximum wear. These projections extend through the shell, and suitable gaskets 23

may be used for preventing any leakage 65 around the projections. Each projection is provided with a bore or socket 24 which extends into the body of the liner a sufficient distance so that when the liner becomes worn to a dangerous point the bore 70 will be opened to permit the leakage of material from the mill to give an indication.

The modifications illustrated and described above are some of those in which the invention may be embodied, but it will 75 be understood that it may also be embodied in other forms, and that various changes in the details of construction of the particular arrangements illustrated may be made without departing from the principle of the invention as defined in the appended claims.

I claim:

1. In a ball mill, a shell, liners mounted on the inside of said shell, and a sentinel device provided with a bore associated with 85 said shell, which, when worn away a certain amount, allows material to escape from the inside of said shell to the outside thereof.

2. A ball-mill comprising a shell, liners 90 secured upon the inside of the shell, and hollow members associated with the liners and extending into the same a sufficient distance to permit their bores to be exposed when the liners wear away to a predetermined degree.

3. In a ball-mill provided with a shell having liners secured upon its inside, the combination of hollow members projecting 100 through the shell and having their inner ends within the liners so that when the liners wear away the bores of the members will be placed in communication with the interior of the shell to permit leakage of the contents of the mill to give an indication of the worn condition of the liners.

4. In a ball-mill provided with a shell having liners secured upon its inside, the combination of bolts having their heads countersunk in the liners at the zone of 110 maximum wear and their shanks projecting through the wall of the shell, each of said bolts being formed with a socket extending into the portion of the bolt that lies within the liner so that as the liners wear away the sockets will be placed in communication with the interior of the shell to permit leakage of the contents of the mill to give an indication of the worn condition of the liners.

5. A ball mill, comprising a shell, a liner within said shell and means adapted to secure said liner to said shell, having a bore leading from outside said shell to within said lining.

In testimony whereof I affix my signature.

EDWIN H. SCHMIDT.
